UNITED STATES PATENT OFFICE.

JOHN F. DUDGEON, OF NORFOLK, NEBRASKA.

RADIATOR-PROTECTOR.

1,338,614.

Specification of Letters Patent. Patented Apr. 27, 1920.

Application filed May 6, 1919. Serial No. 295,161.

To all whom it may concern:

Be it known that I, JOHN F. DUDGEON, a citizen of the United States, residing at Norfolk, in the county of Madison and State of Nebraska, have invented new and useful Improvements in Radiator-Protectors, of which the following is a specification.

This invention has reference to a protective device for the radiators of motor driven machines.

In carrying out my invention it is my purpose to arrange on the outer face of a radiator a spring actuated curtain and to provide the radiator with means whereby the said curtain may be held in any desired extended position to entirely, or partly cover the radiator.

It is a further object of the invention to produce a device of this character which may be readily attached to the front of any ordinary construction of radiators, including a curtain spring actuated in one direction, the said curtain being mounted in a suitable casing which protects the same, while on the radiator is arranged means for holding the curtain in adjustable extended positions, the spring actuating the curtain exerting a tension sufficient to hold the curtain tight against the outer face of the radiator when wholly or partly covering the radiator and also to retain the said curtain in the casing when in wound condition.

In the drawings:

Figure 1 is a front elevation of a radiator illustrating the application of the improvement.

Fig. 2 is a side elevation thereof.

Fig. 3 is a sectional view approximately on the line 3-3 of Fig. 1.

Fig. 4 is a perspective view of the strap employed for holding the curtain adjusted.

Fig. 5 is a similar view of the metal plate hanger.

Fig. 6 is a similar view of the roller casing.

To the bottom of the radiator casing 1 of a radiator 2 I attach a cylindrical casing 3. This casing is preferably constructed from a single piece of metal as illustrated in Fig. 6 rolled upon itself to provide the cylindrical body and bent to provide the round ends 4 and angle ears 5 at the ends. The casing is preferably provided with an extending portion at the front thereof which is indicated by the numeral 6, the latter being substantially V-shaped and being centrally provided

with a bolt opening 7 to receive the bolt or stud that may be secured to the lower portion of the casing 1. The ears are provided with openings receiving securing elements 60 for attaching the ends of the casing to the sides of the radiator casing. The ends 4 are provided with bearing openings for the trunnions 8 of a spring actuated roller 9. Around this roller is wound a curtain 10. 65 The curtain passes through a suitable opening in the roller casing 3 and has its outer end connected with a metallic plate 11 that is centrally bent upon itself to form a reduced hook 12.

Arranged over the front of the radiator is a metallic strap 13, the same having its lower end provided with an elongated slot 14 through which passes the bolt 15 that secures the lower projecting portion of the roller casing to the radiator casing. The strap 13 is provided with spaced apertures 16. The strap, at the outer or upper end thereof is enlarged and formed with a round eye portion 17. The strap is bent over the top of the radiator so that the water inlet 18 for the radiator is received in the eye 17.

The spring actuates the curtain roller in one direction only, so as to wind the curtain thereon. In accordance with weather conditions the metallic plate 11, which really provides a hand hold for the curtain, is grasped and the curtain is unwound from the roller over the face of the radiator a determined length, the hook 12 entering one of the openings 16 of the strap 13. By this arrangement it will be seen that the radiator may be protected from an inflow of cold air, in winter seasons and that the amount of air passing through the radiator may be regulated.

It is thought, from the foregoing description, when taken in connection with the drawings that the simplicity of the construction and the advantages thereof will be apparent without further detailed description.

Having thus described the invention, what is claimed as new, is:—

1. In combination with a radiator, a wind protector therefor, comprising a casing secured to the radiator at the lower portion thereof, a spring actuated roller journaled in said casing, a curtain on said roller and having one of its ends projecting through said casing, and provided with a hook, a member on the outer face of the radiator

having spaced apertures, and the hook of the curtain designed to engage with any of said apertures to hold the curtain withdrawn from the roller partly or wholly over the 5 face of the radiator.

2. In combination with a radiator, a wind protector therefor, comprising a casing secured to the outer face of the radiator at the lower portion thereof, a spring actuated 10 roller journaled in the casing, a curtain having one end secured on said roller and its other end projecting through the casing, a

plate on the outer end of the curtain having a hook, a strap on the outer face of the radiator having its lower portion secured to the 15 radiator by one of the elements which connect the casing to the radiator and its other end provided with a ring positioned on the water inlet spout for the radiator, and said strap having spaced apertures which are 20 designed to receive said hook.

In testimony whereof I affix my signature.

JOHN F. DUDGEON.
